Specification of Letters Patent. Patented Feb. 24, 1914.

Application filed May 20, 1910. Serial No. 582,401.

To all whom it may concern:

Be it known that I, CHARLES A. DAHL, a citizen of the United States, and resident of Roxbury, county of Suffolk, State of Massachusetts, have invented an Improvement in Buttonhole-Sewing Machines, of which the following description, in connection with the accompanying drawing, is a specification, like characters on the drawing 10 representing like parts.

This invention relates to sewing-machines particularly adapted for overstitching the edges of buttonholes and other openings in material, and it has for its object the production of a buttonhole-sewing machine of very simple construction and which can be run at high speed, so constructed and arranged that a two-thread overseam is formed with a single eye-pointed needle operating 15 in conjunction with a single combined looper and spreader.

In the machine embodying my present invention the upper thread is carried by a vertically reciprocating and laterally vibrated needle which penetrates the work from above, and the loop of needle-thread below the work, on the thrust of the needle for the edge as well as for the depth stitch, is engaged by a complementary member of 20 the stitch-forming instrumentality located below the work, such member carrying the under thread, which latter is brought into such coöperative relation with the needle-thread as to form therewith a stitch of the 25 overseam.

The work is held in a suitable work-clamp, and I have chosen to illustrate my invention in connection with a work-clamp which is given a movement in the direction of the 30 length of the buttonhole and also a lateral movement relative thereto, as in United States Patent No. 714,284 granted November 25, 1902 to me and another; and as in my prior Patent No. 749,776 granted January 19, 1904. Herein, as in said patents, the stitching is commenced at or near one end of the buttonhole and is carried along one side thereof; the work-clamp is then shifted laterally to place the work in position for 35 the barring stitches, and thereafter the movement of the work-clamp lengthwise of the buttonhole is reversed, while stitches for the second side of the buttonhole are made.

The longitudinal movement of the work-

clamp is then stopped and other barring stitches are made to complete the buttonhole, and the clamp is then moved laterally to place it into its normal or starting position. In the two patented structures referred to, however, the stitch is made by a single thread, forming a chain-stitch of well known construction, whereas in my present invention a stitch composed of concatenated loops is formed by the needle and under threads, and this is effected irrespective of the direction of feed of the work, without any relative turning movement between the work and the stitch-forming instrumentality, either or both.

In the present invention I provide an upper-thread loop-forming mechanism and a complementary under-thread mechanism which is arranged to form loops in the under thread and actuating mechanism for said parts by which the loops of upper thread are inserted alternately through previously formed loops of upper thread and loops of under thread. Said complementary under-thread mechanism is located below the work and is so constructed and arranged that it spreads and holds the loops of both the upper and under threads at the same time and so positions such spread loops with relation to the needle that on one thrust the needle will enter its own loop and on the next thrust it will enter the loop of under thread.

The complementary member as herein shown is made in two parts which are movable bodily in unison and they also have a relative movement toward and from each other, similar to the opening and closing movements of a pair of scissor-blades. When said parts are closed the complementary member acts as a looper to enter the loop of needle-thread below the work, and when said parts are separated such complementary member acts as a loop spreader, to spread the loops of upper and under thread and to hold them spread while one or the other of such loops is placed in proper position relative to the needle on its next thrust or work-penetrating stroke. Thus such complementary member is a combined looper and spreader, and it also is a loop holder and positioner, as will appear more fully hereinafter.

In the drawings I have illustrated my

present invention in connection with a buttonhole-sewing machine such as is shown in my prior Patent No. 749,776 it being understood that the needle, the actuating mechanism therefor, and the work-clamp and its movements to feed the work in the formation of the buttonhole form no novel features, *per se*, of this invention but in practice are all substantially as in the patent just referred to.

The various novel features of my present invention will be fully described in the subjoined specification and particularly pointed out in the following claims.

15 Figure 1 is a front view of a sufficient portion of a buttonhole-sewing machine to be understood, showing primarily the needle-actuating mechanism of the stitch-forming instrumentality, the base of the machine 20 being broken off; Fig. 2 is a left hand elevation of the mechanism illustrated in Fig. 1, the novel portion of the mechanism for controlling the under thread and operating in conjunction with the needle to form the 25 stitch being indicated in dotted lines; Fig. 3 is a much enlarged underside view of the combined looper and spreader and the mechanism for actuating the same, all located beneath the bed-plate of the machine and below 30 the work; Fig. 4 is a transverse section of such devices taken on the irregular line 4-4, Fig. 3; Fig. 5 is a rear elevation of the combined looper and spreader which constitutes the member of the stitch-forming 35 instrumentality complementary to the eye-pointed needle; Fig. 6 is a top plan view thereof; Fig. 6^a is a top plan view of one of the parts of the said complementary member; Fig. 7 is an enlarged underside view 40 of such complementary member acting as a looper and about to enter the loop of needle-thread, the needle being down; Figs. 8 to 13 are similar views, but much enlarged, of the complementary member in the various 45 positions assumed during the stitch-forming cycle, the said member having returned to the position shown in Fig. 7 after the cycle is completed, the position corresponding to that shown in Fig. 13; Figs. 14 and 15 are 50 views on a still larger scale of the concatenated upper and under threads during the formation of the stitch, and correspond to the illustrations thereof in Figs. 10 and 11, respectively; Fig. 16 is an enlarged view, 55 on the same scale as Figs. 14 and 15, of the completed stitch but before the interlocked loops of upper and under thread have been drawn taut; Fig. 17 is a separate view in side elevation of the cam disk and its cam 60 groove for controlling the movements of the complementary member, the follower roll being indicated by dotted lines.

The terms "needle-thread" and "upper thread" are herein used interchangeably, it 65 being understood that in the present em-

bodiment of my invention the upper thread is the one carried by the needle, while the under thread is the one carried by the complementary member of the stitch-forming instrumentality.

70 Referring to Figs. 1 and 2 of the drawings, the bed-plate A² is hinged at A' on the base frame A; and a standard A² on the bed-plate is provided with an overhanging arm 75 having bearings to sustain a rock-shaft B² deriving its motion from the main shaft A² through usual connections not shown and forming no part of this invention.

At its front end the shaft B² has an arm 80 B² connected by a link B⁷ with a stud projecting from a collar B⁸ secured to the upper end of the needle-bar B¹⁰, the latter being vertically reciprocated in a guide C and carrying at its lower end an eye-pointed needle F.

85 G¹ is the cutter, mounted on its carrying-lever H¹ and actuated in usual manner.

The guide C embracing the needle-bar is contained in a tubular portion 71 of a radius-bar 72 fulcrumed on a stud 73 suitably mounted on a bracket at the front end of the overhanging arm of the machine, and to provide for the lateral vibration of the needle-bar throughout the stitching of a buttonhole the radius-bar is connected with 90 an adjustable link 74. Said link is connected at 75 to a rocking sleeve 76 fulcrumed on the rock-shaft B², a projection 77 of said sleeve being adjustably connected by a stud 78, Fig. 2, with a link 79 operatively connected with and longitudinally reciprocated by the main shaft A², the rocking of the sleeve 76 acting through the link 74 to vibrate the radius-bar 72 and thereby effect 95 the lateral vibration of the needle-bar after 100 each descent thereof.

The work-clamp comprises a longitudinally-movable plate 36 overlapped at its edges by guide-plates 37 attached to the bed-plate A², said plate 36 in practice being 110 slotted to embrace the cutting-block (not shown), toothed portions 42 of the plate contacting with the under side of the work held in the clamp by the pressure against its upper side exerted by feet 43. Said feet 115 are carried by arms 44, 45 connected with a block 47 mounted on a stud 48 in ears at the rear end of the plate 36, said block having extended backwardly from it an arm 49, and each of the arms 44, 45 is acted upon 120 by a spring 50, all as in my Patent No. 749,776 hereinbefore referred to.

The work having been clamped in the work-clamp and the machine having been started the said work-clamp is first moved longitudinally in the direction of the length of the buttonhole, (to the left, Fig. 1) during which time the stitch-forming instrumentality operates to stitch one side of the buttonhole, the lateral vibration of the

needle causing the formation of depth and edge stitches alternately, after which the work-clamp is shifted to position the work for the barring stitches. Then the work-clamp is moved in the direction of the length of the buttonhole, but opposite to its original motion, (to the right, Fig. 1) while the stitches for the second side of the buttonhole are made, and the end is barred, such movements of the clamp, and its final lateral shift to original starting position in readiness for the stitching of the next buttonhole, being effected substantially as in the before mentioned patents.

15 The needle-thread tension device comprises essentially a lever 91 fulcrumed at 90, Fig. 1, and carrying a suitable spring-controlled tension device 92, and the extension 95 of lever 91 has attached to it a spring 96 connected at its other end to the short arm of a lever 97 fulcrumed at 98 on the standard A³. The longer arm of the lever is notched to engage a stop 99 on the extension 95 and hold the tension device in the position shown 25 in Fig. 1, the position in which it is left after stitching the first half of a buttonhole and when the machine is stopped at the completion of a buttonhole.

The manually-controlled starting-lever 30 101 when depressed slides the rod H¹² to the left to shift the driving belt onto the fast pulley A⁵ to start the machine, and at the same time arm 103 of the starting-lever acts on lever 97 to disengage its longer arm from 35 the stud 99, permitting the spring 96 to move the tension device 92 toward the needle-bar, while by suitable means (not shown) the springs 50 act to close the work-clamp and clamp the work therein, all as in Patent 40 No. 749,776.

From the tension device 92 the needle-thread passes through an eye in a suitable take-up arm 92^x, Fig. 2, and leads thence directly to and through the eye of the needle E.

I will now describe the novel features of my invention whereby the under thread is controlled and concatenated with the needle-thread to form an overseam, the two devices 50 immediately coöperating to that end being the eye-pointed needle carrying the upper thread and a complementary member carrying the under thread and combining in itself the functions of a looper, loop-spreader, and 55 positioner for the loops of thread.

The main shaft A⁴ near its outer or left hand end, viewing Fig. 1, has fast thereon a cam disk M, Figs. 2, 3, 4 and 17, provided in its outer face with a peculiarly shaped 60 cam groove indicated as a whole at M^x, Fig. 4, to receive a follower roll or other stud m extended from a rod m' mounted to reciprocate longitudinally in a fixed bearing m^x on the under side of the bed-plate A², the rear 65 end of said rod being forked at m² to slid-

ingly embrace the main shaft between the cam disk M and the shaft bearing A⁵, Fig. 3. Herein this rod is shown as reciprocated at right angles to the direction of the length of the buttonhole to be made, and at its front end said rod carries a fixedly attached, upright collar m³ having at its upper end an upright pivot stud m⁴ to which is pivotally connected one end of a link m⁵, the other end of the link being pivotally connected at m⁶ with a looper-carrier. This looper-carrier is herein shown as a horizontally swinging arm m⁷ provided with a long hub m⁸ fulcrumed on a stud m⁹ depending from the bed-plate beyond the outer or left hand end of the throat-plate T, Fig. 3, said throat plate being longitudinally slotted and having an enlarged lateral needle opening T^x.

The free end of the looper-carrier has fixedly attached to it by a suitable screw m¹⁰ the under thread carrying complementary member of the stitch-forming instrumentality, to be presently described, such member swinging as a whole in a path transverse to and adjacent the path of the needle in its thrusts for both depth and edge stitches.

Referring to Figs. 4 and 17 the cam groove M^x has two opposite circular portions m¹¹, m¹², of like radii which determine the point to which the complementary member is retracted after each descent of the needle, the dwell periods during which such member is at rest being governed by the length of said portions.

In the position of the parts shown in Figs. 3 and 4 the complementary member is fully retracted and at rest in the position corresponding to Fig. 7, but ready to move forward to take a loop of needle-thread, such forward stroke being effected when the roll m moves toward the shaft A⁴ by traversing the part m¹³ of the cam groove, a corresponding portion m¹⁴ diametrically opposite effecting the next forward stroke, it being understood that for each revolution of shaft A⁴ the needle makes two descents, for depth and edge stitches, and the complementary member makes two complete oscillations, taking a loop of needle-thread on each forward stroke.

Fig. 8 shows the position of the complementary member when the deepest portion of the part m¹³ governs the roll m, and Fig. 11 shows its position when the deepest portion 120 of part m¹⁴ is acting upon the roll m. From the middle of the part m¹³ there is a short, quick rise to partially retract the complementary member to the position shown in Fig. 9, and the complete retraction to the position shown in Fig. 10 is effected by the part m¹⁵ of the groove, so that one oscillation of the carrier m⁷ is completed when the roll m enters the part m¹² of the groove. After the dwell m¹² the roll m traverses the part m¹⁴ 130

and approaches the shaft A^4 , the complementary member moving forward to take the second loop of needle-thread, and the end of such stroke places the parts in the position shown in Fig. 11 when the roll is at the low point of the part m^{14} of the groove. Now a short retractive movement to the position shown in Fig. 12 is necessary, for reasons to be described, followed by a short 10 dwell and then the completion of the retractive movement, the initial retraction, dwell, and final retraction being effected by the portions m^{16} , m^{17} and m^{18} , respectively, of the cam groove, the cycle being completed when 15 the roll m reaches the long dwell m^{11} .

The substantially L-shaped complementary member is herein shown as comprising a shank l^6 having a tapered, lateral extension l constituting the looper, and a loop spreader 20 s , a headed pivot-stud 2 rotatably mounted in a hole 3, Fig. 6^a, in the enlarged base of the looper and screwed into the spreader s , Fig. 5, serving to pivotally connect the spreader and looper.

25 The loop spreader rests upon the flat face of the looper, Figs. 5 and 6, and has a depending tail s' engaged by one end of a light spring s^2 coiled around the stud 2 between its head 4 and the under face of the looper, 30 the latter carrying a depending pin 5 engaged by the other end of said spring, the spring being so wound as to normally hold one edge of the spreader against a shoulder 6 on the looper shank l , as in Fig. 6, this 35 closed position of the looper and spreader being shown as viewed from the opposite side in Figs. 7, 10 and 13.

The outer edge of the looper has a loop-arresting shoulder 7, extending across its 40 lower face, and a diagonal eye 8 is formed in the looper, passing through the shoulder, while a second eye 9 is formed in the looper transversely thereof near its point or tip, through which the under thread t is led to 45 the stitch-forming point.

In Figs. 7 to 16 inclusive the underthread t is indicated by a thick black line, to distinguish it from the upper or needle thread n .

50 Two notches 10, 11 are made in the outer edge of the spreader, the notch 10 being substantially opposite the shoulder 7 and notch 11 opposite the eye 9 of the looper.

From the foregoing description, and also 55 by referring to the enlarged detail views Figs. 7 to 13, it will be seen that the spreader has a movement in unison with the looper and also a lateral swinging movement relatively thereto upon the stud 2 as a fulcrum, 60 said stud not only connecting the said parts but also supporting the spreader-closing spring s^1 . When the spreader is closed it lies above and upon the looper, with its tip closely approaching the tip of the looper, 65 as shown in Figs. 5 and 6, said parts being

rounded over or convexed at their edges to readily enter the loop of needle-thread in forming the stitch.

The end of the loop spreader adjacent its depending tail s' is cam-shaped, at s^2 , best 70 shown in the large detail views, to be intermittently engaged by a spreader-opener, shown as a finger s^3 , having an elongated and deep flat engaging portion s^4 , Fig. 3, and fixedly mounted on a lever s^5 fulcrumed at s^6 on the bearing m^8 , as herein shown. Beyond the fulcrum stud s^6 the lever is extended at s^7 above the main shaft A^4 and provided with a roller or other stud s^8 which is held by a spring S^9 , (partly shown 80 in Fig. 3) against the adjacent flat face of the cam disk M or against diametrically opposite cam lumps s^9 , s^{10} thereon, symmetrically located with respect to the dwell portions m^{11} , m^{12} , of the cam groove m^8 . When 85 either of said cam lumps engages the roll s^8 the enlarged end s^4 or finger s^3 is swung toward the looper-carrier m^7 and the face of the finger end s^4 is engaged by the cam portion s^2 of the loop-spreader s , to open the 90 latter and hold it open during a portion of its movement with the looper. Such opening of the loop-spreader occurs after the looper and closed spreader have entered a loop of needle-thread and is maintained until after the needle on its next descent through the work has passed through one or the other of the two spread loops of 95 needle and under thread.

It is to be understood that the particular 100 mechanism shown and described herein for controlling the oscillation of the looper and loop-spreader is illustrative only, and that any other suitable mechanism for securing the requisite motions of the parts may be 105 employed without departing from the spirit and scope of my invention.

The under thread t is led from a source of supply to a suitable tension device t^2 , Fig. 3, and thence to a guide t^3 and a spring 110 take-up t^2 , from which the thread leads to the eyes 8 and 9 of the looper, and as is usual in buttonhole-sewing machines the free end of the under thread is carried up through the needle-opening T^* of the throat-plate T to the top of the bed-plate before the stitching is commenced.

The eye-pointed needle E^* is supplied with needle-thread n as shown in Figs. 1 and 2, and after the work is clamped in the work-clamp the machine is started and the stitching 115 of the button-hole is effected.

The stitch-forming cycle is illustrated in Figs. 7 to 13, in connection with Figs. 14 to 16, and in Fig. 7 it is supposed that the 120 needle has descended through the material in its path nearest the back of the machine, and then has risen sufficiently to throw out a loop n' of needle-thread. The looper and closed spreader now move forward and enter 125

130

such loop n' , and in so doing carry a bight of the under thread t through said loop and form an under thread loop t' , and the loop-spreader s is opened, by coöperation of the 5 part s^2 and the end s^4 of the finger s^3 , to spread the two loops, Fig. 8, the needle having risen when the needle-thread loop n' was taken by the looper and closed spreader, one side of each loop n', t' being held by 10 the looper l as the spreader s is opened or swung away from the looper. By the forward movement of the looper and closed spreader the loop n' is drawn against the shoulder 7 on the looper and as the spreader 15 is opened the notches $10, 11$ thereof engage and hold the two loops n', t' as they are spread, see Fig. 8. Still holding the loops spread the looper and spreader are retracted far enough to enable the needle on its 20 next descent, (the needle having been shifted laterally while above the work) to pass through its own spread loop n' , the points of penetration of the needle in the work being indicated at c and d respectively, the 25 direction of feed of the work being indicated by arrow F^{100} .

Comparing Figs. 8 and 9 it will be seen that first the spread loop n' is at one side of the point d from which the loop sides lead, 30 and thereafter by retraction of the looper and spreader, the loop n' is carried to the opposite side of the needle penetrating point d , as appears in Fig. 9, but the relative position of the bases of the loops n' and t' is not 35 changed.

While the parts are in the position shown in Fig. 9, and after the needle descends at c through its own loop n' , the looper and spreader are further retracted to the position 40 shown in Fig. 10, (which is the same as shown in Fig. 7) the continued descent of the needle casting off the loop t' from the looper and spreader as the latter closes. When the loop t' is thus cast off from the looper and spreader it is drawn out of the loop n' , and the free side of such loop t' is drawn around the needle above the loop n' as the latter is cast off onto the needle, as shown in Fig. 10. As the needle begins to 45 rise and throw out a second loop n^2 of needle-thread, Fig. 10, the looper and closed spreader are moved forward or advanced to enter or take such loop n^2 and carry a bight of the under thread through it, as before, the loop n^2 sliding along up to the shoulder 50 7 , and after the loop n^2 has been taken the needle rises and is shifted again, the rise of the needle taking the sides of the loop n^2 up through the loop n' , while the spreader 55 opens and spreads the loop n^2 and the second loop t^2 of under thread, as depicted in Fig. 11. In practice the sides of the spread loops n^2 and t^2 will be substantially taut, but in order to clearly illustrate the relationship 60 between the various loops in Fig. 11 I

have distorted the right hand sides of the loop n^2, t^2 so that they appear slack, as otherwise the drawing would be much confused. During this ascending needle movement the looper and spreader have been retracted, but for a shorter distance than when the loop n' was positioned as in Fig. 9, to the position shown in Fig. 12, so that the descending needle will pass through the loop t^2 of under thread and wholly outside of the loop n^2 of needle-thread. The retractive movement of the looper and spreader is now resumed and completed and the spreader closes, the loop n^2 as it is cast off being looped around the sides of the under thread loop t^2 while the said loop t^2 is carried around the needle, as in Fig. 13, the rise of the needle throwing out a third loop n'^x to be entered on the next forward stroke of the looper and spreader. 70 75 80 85

When the complemental member reaches the position shown in Fig. 13 the cycle is completed, the operations described being repeated in regular order as the stitching proceeds, the loop n'^x , Fig. 13, corresponding in the next cycle to the loop n' , Fig. 7, of the cycle just described. 90

From the above description it will be seen that the machine herein shown comprises an upper-thread loop-forming mechanism in the form of an eye-pointed needle which forms a succession of loops in the upper thread, a complemental under-thread mechanism herein shown in the form of a thread-carrying looper and spreader and means for actuating said parts whereby the loops of upper thread are inserted alternately through previously formed loops of upper thread and loops of under thread. 95 100

The concatenation of the threads in the formation of the stitch during the cycle is well illustrated in Figs. 14, 15 and 16, and in Fig. 16 the completed stitch is shown before it has been set, with the two threads interconnected to form the overseam, as will be manifest, it being practically impossible to illustrate in an intelligible manner the stitch when completely set and the threads drawn taut. In Figs. 8 and 9 the part t' of the under thread is actually in loop form, while in Fig. 10 this same part is shown as but slightly bent around the needle, the reference character t' being still retained for such part, and also in Figs. 11 and 12, said part in these figures being bent about one of the sides of the needle-thread loop n^2 and continuing thence to the second loop t^2 of the under thread. 110 115 120 125

Whether the first or the second side of the buttonhole is being stitched the stitch-forming cycle is the same, as is also the case when barring, for the complemental member takes off the loop of needle-thread after each needle thrust, and the spreading, holding, and casting off of the loops of upper and 130

under thread follow in regular sequence, as described.

The cycle illustrated happens to be taken when the second side of the buttonhole is being stitched, and consequently the feed of the work is against or opposite the draft of the needle-thread, but the operations performed are precisely the same during the stitching of the buttonhole along its first side, save that the work is fed opposite arrow F^{100} , Fig. 9, or with the draft of the needle-thread. By the draft of such thread I mean the direction thereof as it leads through the eye of the needle, which is from right to left, viewing Fig. 1.

The needle-thread loop when spread is triangular in shape, Figs. 8, 9, 11 and 12, the base of such triangle extending from the outer edge of the looper l to the outer edge of the spreader s , so that a wide clearance space is always presented for the passage of the needle through such loop on alternate thrusts, and this, together with the fact that the needle always enters its own loop between the base of the latter and the last previous penetration of the material by the needle, enables the stitching to be performed with equal facility on both sides of the buttonhole. This arrangement of the needle-loops enables the stitches to be drawn taut or set just as easily and effectively when the work is fed against the draft of the needle-thread as when the feed is with the draft, so that the machine can be run at high speed, up to say 3000 stitches, per minute.

Viewing Fig. 12 it will be seen that the needle passes through the loop l^2 of under thread between its base and the last previous penetration of the material by the needle, as pointed out with regard to the loops of needle-thread, and with similar results as regards forming and setting the stitch.

The structure of the complemental member is very simple, and its movements as a whole, together with the opening and closing of the loop-spreader forming a part of such member, are controlled and effected primarily by two cam devices, viz: the cam groove M^1 and the cam lumps s^a , s^b on the face of the cam disk M .

The designation of the parts l and s as the looper and loop spreader respectively is for convenience, for it must be obvious that when said parts are closed both of them enter the loop of needle thread and carry a bight of the underthread therethrough. Manifestly neither part could spread the loops were it not for the cooperation of the other part, inasmuch as loop spreading is merely the opening out or separating of the sides of a loop, but as the part s is the one which herein is actually swung it is referred to as the spreader, and these two members l and s , only, by their simultaneous and relative

movements and changes of position perform all the required functions.

It will be understood from the foregoing description and the drawings that thrusts of the needle to form depth stitches at one side of the buttonhole will form edge 70 stitches when the opposite side is being stitched, and in like manner the thrusts for edge stitches at one side will form depth stitches at the other side. This necessarily follows when it is remembered that the needle reciprocates in two fixed parallel and upright paths, first in one and then in the other path as it is vibrated laterally, the work being shifted bodily and laterally with relation to such paths to accomplish the 80 stitching at the two sides of the buttonhole and effect the barring thereof. The points e which indicate the points of penetration of the needle in one of its paths are staggered with relation to the points of penetration of the needle in its other path, such latter points being indicated at d , and this is very clearly shown in Fig. 16.

The forward or loop-taking stroke of the complemental member is always continuous 90 from beginning to end, but the return or retractive stroke is temporarily arrested to enable the needle to enter a spread loop, and such retractive stroke is then resumed and completed before the needle rises, the 95 initial retractive movement when a loop of needle-thread is to be entered being longer than the initial retractive movement when a loop of under thread is to be entered by the needle, owing to the different positioning necessary for such loops.

Various changes or modifications in details of construction and arrangement may be made by those skilled in the art without departing from the spirit and scope of my invention as set forth in the claims annexed hereto.

Having fully described my invention, what I claim as new and desire to secure by Letters Patent is:—

1. In a buttonhole-sewing machine provided with a work-clamp movable in the direction of the length of the buttonhole for the stitching of the sides thereof and laterally movable for the barring stitches, a two-thread stitch-forming instrumentality to form an overseam, said instrumentality including a vertically reciprocating and laterally vibrated eye-pointed needle, and a complemental member comprising a single 115 looper and a loop-spreader cooperating therewith, said looper and spreader entering and spreading every loop of thread thrown out by the needle.

2. In a buttonhole-sewing machine provided with means to move the work in the direction of the length of the buttonhole, for the stitching of the sides thereof, a re-

ciprocating and laterally vibrated eye-pointed needle carrying the upper thread, a single looper coöperating therewith and carrying the under thread, and a loop-spreader movable with and also relatively to the looper, said looper and spreader entering and spreading every loop of needle thread and the looper carrying a bight of under thread through each of the upper thread loops in the formation of an overseam.

3. In a buttonhole-sewing machine, the combination with a work-clamp and means for moving it in the direction of the length of the buttonhole during the stitching of one side thereof and to reverse such movement during the stitching of the opposite side thereof, of an upper-thread loop-forming mechanism, means to actuate it to form loops of upper thread alternately in different positions horizontally, under-thread loop-forming mechanism coöperating with the upper thread loop-forming mechanism to form an overseam composed of concatenated loops of upper and under thread, said under thread loop-forming mechanism including a single combined looper and spreader device, means to cause said looper and spreader device to enter every loop of upper thread and to carry a bight of the under thread therethrough and thereafter to spread simultaneously a loop of each thread.

4. In a buttonhole-sewing machine provided with a work-clamp movable in the direction of the length of the buttonhole and at right angles thereto, stitch-forming mechanism comprising a reciprocating and laterally vibrated eye-pointed needle above the work, a single looper and a single loop-spreader, both below the work, the looper carrying the under thread, and means to actuate said looper and spreader in coöperation with the needle to enter and spread each loop of needle thread and to present loops of needle thread and under thread alternately to be entered by the needle.

5. In a buttonhole-sewing machine, the combination with a clamp to clamp and move the work, of a two-thread stitch-forming mechanism including upper-thread loop-forming mechanism adapted to form loops of upper thread in two different positions, a looper carrying the under thread, a loop-spreader movable with and also relative to said looper, means to cause said looper and loop-spreader to enter each loop of upper thread and carry a loop of under thread therethrough, and means to effect relative movement of said looper and spreader to spread simultaneously loops of upper and under thread.

6. A thread-carrying needle to penetrate the work to form alternately depth and edge stitches of a buttonhole, and complemental

means co-acting with the needle, comprising a single under thread-carrying looper, a loop-spreader carried thereby, said looper and spreader engaging the loop of needle-thread at each descent of the needle and taking the under thread through such loop, means to open the spreader and spread simultaneously the loops of needle and under thread at each ascent of the needle, and means to position the said looper and open spreader for the needle to enter its own spread loop on one descent and to enter the spread loop of under thread at its next descent.

7. A thread-carrying needle to penetrate the work to form alternately depth and edge stitches of a buttonhole, a complemental member co-acting with the needle carrying an under thread, said member entering each loop of needle-thread and taking the under thread therethrough at each descent of the needle, means to cause said member to spread the loops of both threads at each ascent of the needle, and means to impart a variable movement to said complemental member to present the open loop of needle-thread for the entrance of the needle on one descent thereof and to present the open loop of underthread for the entrance of the needle on its next descent.

8. A thread-carrying needle to penetrate the work to form alternately depth and edge stitches of a buttonhole, and complemental means co-acting with the needle, comprising: under thread-carrying looper, a loop-spreader pivotally mounted on the looper, said looper and spreader engaging the loop of needle-thread at each descent of the needle and taking a loop of under thread through such loop of needle-thread, means to thereafter open the spreader and hold the loops of needle and under thread spread for the next descent of the needle, and means to position said looper and open spreader to enable the needle on one descent to penetrate its own spread loop and on the next descent to penetrate the spread loop of under thread.

9. A thread-carrying needle to penetrate the work to form alternately depth and edge stitches of a buttonhole, and complemental means co-acting with the needle, comprising a single under thread-carrying looper, a loop-spreader pivoted on and movable toward and away from the tip of said looper, a spring to close the spreader, the said looper and closed spreader taking the loop of needle-thread at each descent of the needle and taking a loop of the under thread through such loop of needle-thread, means to open the spreader thereafter and maintain it open until the next descent of the needle, to spread the loops of needle and under thread embracing the looper and spreader, and means to effect a complete os-

cillation of the looper and spreader for each reciprocation of the needle and temporarily arrest said looper and spreader on each retractive stroke to present the spread loop of needle-thread to be penetrated by the needle on one descent and on the next descent thereof to present the spread loop of under thread to be penetrated by the needle.

10. A needle-bar having an eye-pointed

10 needle, and means to reciprocate and laterally vibrate said needle-bar, for the formation of edge and depth stitches alternately, combined with a thread carrying looper, means to oscillate it to take the loop of needle-thread at each descent of the needle and carry the under-thread through such loop, said means including a device to temporarily arrest each retractive stroke of the looper, but at different points on successive 20 retractive strokes, a loop-spreader carried by and movable relatively to the looper, and means to open the spreader after it has entered the loop of needle-thread and maintain it open until after the arrest of the 25 looper on each retractive stroke, to spread simultaneously the loops of needle and under thread, the arrest of the looper causing the needle to enter its own spread loop on one descent and on its next descent to enter 30 the spread loop of under thread.

11. A reciprocating and laterally vibrated needle-bar having an eye-pointed needle, combined with a looper having a loop-spreader pivotally mounted thereon, said 35 looper and spreader entering each loop of needle-thread and taking a loop of under thread therethrough, the tips of the looper and spreader thereafter separating to spread and hold open both loops, and mechanism to 40 actuate the looper and control the opening and closing movement of the spreader relatively to the looper.

12. A reciprocating and laterally vibrated needle-bar having an eye-pointed needle, combined with a looper having a 45 loop-spreader pivotally mounted thereon, said looper and spreader entering each loop of needle-thread and taking a loop of under thread therethrough, the tips of the looper 50 and spreader thereafter separating to spread and hold open both loops, and controlling mechanism to govern the opening and closing of the spreader and the movement thereof bodily with the looper to prevent 55 said a spread loop of needle-thread to be penetrated by the needle on one descent and a spread loop of under thread to be penetrated by the needle on its next descent.

13. A reciprocating and laterally vibrated 60 needle-bar having an eye-pointed needle, combined with an oscillating complemental member co-acting therewith and comprising a single thread-carrying looper and a single loop-spreader, pivotally connected, and 65 adapted to enter each loop of needle-thread,

take a loop of under thread through the loop of needle-thread, and spread both loops simultaneously, and means to govern said complemental member to present on alternate descents of the needle a spread loop of 70 needle-thread to be penetrated thereby and present a spread loop of under thread to be penetrated by the needle on intervening descents thereof.

14. A vertically reciprocating and laterally vibrated eye-pointed needle, to form depth and edge stitches alternately, a looper carrying an under thread, a loop-spreader pivotally mounted on said looper, said looper and spreader engaging the loop of needle thread on each descent of the needle and passing the under thread therethrough, means to separate the tips of the said looper and spreader to spread the loops of needle and under thread as the needle ascends, 85 means to effect a complete oscillation of said looper and spreader bodily for each reciprocation of the needle and temporarily arrest each retractive movement of said loop-engaging parts, but at different points on successive retractive movements, to thereby position a needle-thread loop for penetration by the needle on one descent and to similarly position an under thread loop on the next descent, and a spring to close the spreader with its tip adjacent the tip of the looper prior to each forward stroke of the latter.

15. A vertically reciprocating and laterally vibrated eye-pointed needle, to form depth and edge stitches alternately, combined with a complemental member co-acting therewith and comprising a tapered looper having a transverse eye for the reception of the under thread, a tapered loop-spreader pivotally connected with the looper 105 at its base, and a spring to close the spreader with its tip adjacent the tip of the looper, means to advance the complemental member at each descent of the needle, to cause said looper and loop-spreader to engage and enter each loop of needle-thread, and to retract and temporarily arrest such member at each ascent of the needle, the complemental member being arrested at different points on successive retractive strokes, and a device to co-operate with the spreader and open it after engagement of each loop of needle-thread and maintain the spreader open until after temporary arrest of the looper on its retractive stroke.

16. An eye-pointed needle carrying a thread, and means to cause it to make depth and edge stitches alternately, combined with a co-operating complemental member carrying a second thread, said member comprising two pivotally connected blade-like parts constituting a looper and a loop-spreader and adapted when closed to lie one upon the other, to engage each loop of needle-thread, and mechanism to effect bodily movement of 120 125 130

said complementary member and cause said looper and loop-spreader to enter each loop of needle thread and to control the opening and closing of the said blade-like parts thereof.

17. In a buttonhole stitching machine, the combination with an upper-thread loop-forming mechanism, of complementary under-thread mechanism comprising means to carry a loop of under thread through each loop of upper thread and actuating mechanism for said parts operating to cause the loops of upper thread to be inserted alternately through a previously formed loop of upper thread and a loop of under thread.

18. In a buttonhole stitching machine, the combination with an upper-thread loop-forming mechanism, of complementary under-thread mechanism including means to carry a loop of under thread through each loop of upper thread, and thereafter to spread both loops, and mechanism for actuating such parts operating to cause the loops of upper thread to be inserted alternately through loops of upper thread and loops of under thread while they are spread by said mechanism.

19. In a buttonhole stitching machine, a needle-bar and its eye-pointed needle, combined with complementary under-thread-carrying mechanism comprising a single looper, a single loop-spreader, means to intermittently separate the tips of the looper and spreader, and means, including a cam, to move the looper and spreader in unison forward in a path adjacent the path of the needle and cause them to enter each loop of needle thread and to effect an initial and final retractive movement of said parts from the needle path and temporarily arrest such parts between each initial and final retractive movement while said parts are in the loop of needle thread.

20. In a buttonhole stitching machine, a vertically reciprocating and laterally vibrated eye-pointed needle, combined with complementary under-thread-carrying mechanism, comprising a horizontally swinging looper-carrier, a single looper fixedly mounted thereon, a single loop-spreader, pivotally mounted on the looper, a spreader-closing spring, means to coöperate with and intermittently open the spreader, and means to swing the looper-carrier and effect movement of the looper and loop-spreader in unison toward and from the path of the needle at each reciprocation of the needle, to cause the single looper and loop-spreader to enter and recede from each loop of needle thread.

21. In a buttonhole stitching machine, a vertically reciprocating and laterally vibrated eye-pointed needle, combined with complementary under-thread-carrying mechanism, comprising a single looper having an

eye for the under thread, means to oscillate the looper toward and from the path of the needle at each reciprocation of the needle, to take each loop of needle-thread, a shoulder on the looper to limit movement of the needle-thread loop thereon, a single loop-spreader carried by and movable on the looper, a spring to close the spreader with its tip contiguous to the tip of the looper, and means to coöperate with said loop-spreader during a portion of the oscillating movement of the looper, to open the spreader and separate the tip thereof from the tip of the looper.

22. In a buttonhole stitching machine provided with a work-clamp movable in the direction of the length of the buttonhole and also laterally with relation thereto, in combination, overseam forming mechanism including a vertically reciprocating and laterally vibrated eye-pointed needle, a single combined looper and spreader coöoperating therewith to enter each loop of needle thread and carrying an under thread, and means to cause said combined looper and spreader to spread and present a loop of needle-thread to be entered by the needle on one descent thereof and to spread and present a loop of under thread to be entered by the needle on its next descent.

23. In a buttonhole sewing machine, the combination with a work-clamp, of stitching-forming mechanism forming an overseam composed of concatenated loops of upper and under thread, said mechanism including means to form loops in the upper thread, a single combined looper and spreader device carrying the under thread, actuating mechanism for such parts to cause said looper and spreader device to enter every loop of upper thread and carry a bight of the under thread therethrough and thereafter to simultaneously spread a loop of each thread, and to cause loops of upper thread to be inserted alternately through previously formed loops of upper thread and under thread.

24. In a buttonhole sewing machine, the combination with a work-clamp to clamp and move the work, of a two-thread stitching-forming mechanism including upper-thread loop-forming mechanism, a looper carrying the under thread, a loop spreader movable with and relatively to said looper and actuating mechanism for said parts to cause said looper and loop spreader to enter each loop of upper thread and carry a loop of under thread therethrough, thereafter to effect relative movement of said looper and spreader to spread simultaneously loops of upper and under thread and to insert the loops of upper thread alternately through the spread loops of upper thread and the spread loops of under thread.

25. In a buttonhole-sewing machine, the

- combination with an eye-pointed needle, of
means to reciprocate said needle vertically
and to vibrate it laterally at each recipro-
cation, complementary under-thread mecha-
nism comprising a single combined looper
and spreader device and means to actuate
said parts to cause said combined looper and
spreader device to enter every loop of up-
per thread to carry a loop of under thread
therethrough, to spread both loops and to
position said spread loops so that on alter-

nate thrusts of the needle the latter will
pass through the loops of upper thread
while on the other thrusts of the needle it
will pass through loops of under thread.

In testimony whereof, I have signed my
name to this specification, in the presence of
two subscribing witnesses.

CHARLES A. DAHL.
